TELEVISION ANTENNA

Henry P. Thomas, Schenectady, N. Y., assignor
to General Electric Company, a corporation
of New York

Application February 23, 1939, Serial No. 257,835

6 Claims. (Cl. 250—33)

My invention relates to antennas for radio transmitters, and particularly for transmitters designed for the transmission of a relatively wide band of ultra high frequency oscillations, such as employed in television.

It is an object of my invention to provide an improved television antenna system which radiates horizontally polarized waves having a substantially circular field pattern in the horizontal plane.

It is a further object of my invention to provide an antenna system for television wherein high angle radiations is reduced and the effective transmitted field strength in the horizontal plane over the circular field pattern is increased.

It is another object to provide an antenna system for television wherein the effective transmitted field strength is increased without incurring distortion of the radiation pattern when used for a wide band of frequencies.

A further object is to provide an improved television antenna system wherein radiating elements of the antenna may be so dimensioned and arranged that correctly terminated transmission supply lines for exciting the antenna may be easily provided to prevent standing waves in the transmission lines.

In accordance with the present invention the foregoing and other objects are attained by the provision of an antenna comprising eight radiators or conductors defining a cubical space, the conductors being arranged to form two horizontal squares open at the corners and spaced vertically one from the other, the conductors being energized at opposite corresponding corners of the squares from an oscillation source and in such manner that no distortion occurs in any component of the band of oscillations which is transmitted.

The novel features which I believe to be characteristic of my invention are set forth with particularity in the appended claims. My invention itself, however, both as to its organization and method of operation together with further objects and advantages thereof may best be understood by reference to the following description taken in connection with the accompanying drawing, the single figure of which illustrates partially diagrammatically a radio transmission system embodying my invention.

In the drawing the numerals 1 and 2 designate respectively an antenna arranged in accordance with my invention and a transmitter for supplying oscillations thereto, the transmitter, which may be of 10 kilowatt power, being arranged, for example, to supply oscillations for television transmission in the four and one half meter band. The band width may be of the usual order, of five megacycles, for example.

The antenna 1 comprises eight radiators or

conductors 3 to 10 arranged to form two identical squares 11 and 12 open at the corners, one square directly above the other and the squares spaced apart a distance equal approximately to the length of one of the conductors or to the length of one side of the squares. The conductors 3 to 10 are preferably constituted by hollow bars of conductive material, such as copper, which in the present embodiment may be four inches in outside diameter and approximately one half wave length of the transmitted wave in length, in the present instance approximately seven feet.

To supply the antenna from the source 2, adjacent pairs of conductors 3 and 4 and 5 and 6 of one square 11 are connected respectively at the corners 13 and 14 thereof to the corresponding pairs of conductors 7 and 8 and 9 and 10 of the other square 12 at the corners 15 and 16 thereof. For this purpose a pair of leads 17 are connected respectively between the extremities of the parallel conductors 3 and 7 and between the extremities of the parallel conductors 5 and 9, and a pair of leads 18 are connected between the extremities of the parallel conductors 4 and 8 and between the extremities of the parallel conductors 6 and 10. A pair of bridging leads 19 and 20 connect respectively the midpoints 21 and 22 of the pairs of leads 17 and 18, and a pair of concentric lines 23 and 24 constituting a transmission line 25 connect respectively the midpoints 26 and 27 of the bridging leads 19 and 20 to the oscillation source 2.

The transmission means between source 2 and the pair of antenna conductors at any given corner, as 13, thus comprises the transmission line 25, the transmission line 28 formed by a half section of the bridging leads 19 and 20, and the transmission line 29 formed by a half section of the leads 17 and 18. To prevent standing waves in this transmission means the two adjacent conductors, 3 and 4 in the present case, and the transmission line sections 29, 28 and 25 are so dimensioned and arranged that the impedance of the two adjacent conductors, 3 and 4, equals the surge impedance of section 29, the impedance of section 28 is equal to one half the impedance of section 29, and the impedance of transmission line 25 is equal to one half the impedance of section 28. The same constants hold for the transmission means from source 2 to the other corners 14, 15 and 16, the impedance in general being the same for the transmission means connecting source 2 to each of the pairs of conductors 3 and 4, 5 and 6, 7 and 8, and 9 and 10.

In operation of the transmission system illustrated in the drawing, the wide band of television frequencies being impressed, at opposite corners 13 and 14, and 15 and 16, on the horizontal squares 11 and 12, currents flow in the antenna which are of like phase in all of the conductors 60

3 to 10, as indicated by the arrows. Since the conductors in the horizontal squares are excited cophasally, the radiated energy is horizontally polarized and the horizontal field pattern is of approximately circular form. Since the two identical horizontal squares 11 and 12 are spaced vertically approximately a half wave length of the transmitted oscillations, the substantially circular horizontal beam from the antenna is substantially flattened, the effective strength of the ground signal being therefore substantially increased over that of the ground signal which would be provided by a single square.

In the embodiment of the invention illustrated herein, distortionless radiation of the wide-band ultra-short wave energy suitable for television has been described as attained by the center feeding, from source 2, of the transmission line leads connecting the oscillation source 2 to the opposite superimposed corners of the cubical antenna 1. It will be understood that any other means whereby the squares 11 and 12 may be energized cophasally without incurring distortion in the side bands or other components of the transmitted beam may be employed.

My invention has been described herein in a particular embodiment for purposes of illustration. It is to be understood, however, that the invention is susceptible of various changes and modifications and that by the appended claims I intend to cover any such modifications as fall within the true spirit and scope of my invention.

What I claim as new and desire to secure by Letters Patent of the United States is:

35. 1. In a transmission system comprising a source of oscillations, an antenna comprising eight conductors arranged to form two horizontal squares open at the corners and one directly above the other, the length of said conductors and the distance between said squares being approximately equal to a half wave length of said oscillations, two pairs of vertical leads connecting respectively at two opposite corners of said squares the extremities of opposite conductors of one square to the extremities of the corresponding opposite conductors of the other square, and means to connect one terminal of said source to the midpoints of one of said pairs and to connect the other terminal of said source to the midpoints of 50 the other pair.

55. 2. In a transmission system comprising a source of oscillations, an antenna comprising a set of four conductors arranged to form a horizontal square open at the corners, a second set of four conductors arranged to form a second horizontal square open at the corners directly above said first square and spaced therefrom a distance approximately equal to a side of said squares, two pairs of vertical leads connecting respectively at two opposite corners of said squares the extremities of opposite conductors of one square to the extremities of the corresponding opposite conductors of the other square, a pair of leads bridging respectively the midpoints of said pairs 60 of vertical leads, and means to connect the opposite terminals of said source respectively to the midpoints of said bridging leads.

70. 3. In a transmission system comprising an oscillation source, an antenna comprising two sets of conductors, each set having four conductors arranged in a square open at the corners, said squares being equal and spaced apart one above the other a distance approximately equal to the length of one of said conductors, two pairs of

vertical leads connecting respectively at two opposite corners of said squares the extremities of opposite conductors of one square to the extremities of the corresponding opposite conductors of the other square, and means to connect the terminals of said source respectively to the midpoints of said pairs, said conductors and said vertical leads being so arranged that the impedance of any given adjacent two of said conductors connected to the corresponding section 10 of said vertical leads extending between said two conductors and said connecting means is equal to the surge impedance of said section.

4. In a transmission system comprising a source of oscillations, an antenna comprising eight conductors arranged to form two horizontal squares spaced apart a distance approximately equal to a side of said squares, two pairs of vertical leads connecting respectively opposite conductors of one square to the corresponding opposite conductors of the other square, leads bridging the midpoints of said pair of vertical leads, and a transmission line connecting said source to the midpoints of said bridging leads, said conductors, vertical leads, bridging leads and transmission line being so arranged that the impedance of any given two of said conductors connected to the corresponding section of said vertical leads is equal to the surge impedance of said section, the impedance of that section of said bridging leads between the connection point thereto of said transmission line and said section of said vertical leads is equal to one half said surge impedance, and the impedance of said transmission line is equal to one half the impedance of said section 30 of said bridging leads.

5. In a transmission system comprising a source of oscillations, an antenna comprising eight identical conductors arranged to form two horizontal squares open at the corners, one square being directly above the other and the squares being spaced apart a distance approximately equal to a side of said squares, means to supply current from said source to said conductors at two opposite corners of one square and at two opposite corners of the other square directly above said first-named corners, said means being so arranged that the current in all of said conductors is of like phase, said means comprising connection means between said source and said four corners so arranged that the impedance of said connection means is the same between said source and each of said corners.

6. In a transmission system comprising a source of oscillations, an antenna comprising eight identical conductors arranged to form two horizontal squares open at the corners, one square being directly above the other and the squares being spaced apart a distance approximately equal to a side of said squares, means to supply current from said source to said squares at opposite corners thereof so arranged that the currents in all of said conductors are of like phase, said means comprising two identical transmission lines each constituted by two identical sections, 65 said lines connecting respectively the two opposite corners of one square to the two corresponding opposite corners of the other square, means to connect the connection point of the sections of one of said lines to said source, and means having the same impedance as said last-named means to connect the connection point of the sections of the other line to said source.

HENRY P. THOMAS.
